[57] CLAIM

The ornamental design for a tenderizer, substantially as shown and described.

DESCRIPTION

FIG. 1 is a top perspective view of a tenderizer showing our new design;

FIG. 2 is a bottom perspective view thereof;

FIG. 3 is a side elevational view thereof;

FIG. 4 is a front end elevational view thereof as seen from the right of FIG. 3; and

FIG. 5 is a top plan view thereof.

Fig. 5.
